(Cl. D16—2)

To all whom it may concern:

Be it known that we, Harold Ward, of 25 Broadwalk, Wilmslow, and Frank Dunkerley, of Wadda Hey, Helsby, both in the county of Chester and Kingdom of England, both British subjects, have invented a new, original, and ornamental Design for a Deodorizing Unit for Toilet Flushing Systems or the like, of which the following is a specification, reference being had to the accompanying drawing, forming part thereof.

In the drawing:

Figure 1 is a front view of a deodorizing unit for toilet flushing systems or the like, embodying our new design,

Figure 2 is a side view thereof,
Figure 3 is a rear view, and
Figure 4 is a plan view thereof.

We claim:

The ornamental design for a deodorizing unit for toilet flushing systems or the like, substantially as shown.

HAROLD WARD.
FRANK DUNKERLEY.
